CLAIM

The ornamental design for a gas barbecue, substantially as shown and described.

DESCRIPTION

FIG. 1 is a left front perspective view of a gas barbecue showing my new design;

FIG. 2 is a rear elevational view thereof;

FIG. 3 is a right side elevational view thereof, the left side being a mirror image of the right side;

FIG. 4 is a right front perspective view thereof, in which the gas barbecue is shown in a closed position for carrying purposes;

FIG. 5 is a bottom plan view thereof.

The broken line disclosure in FIGS. 1 and 3 is only for the purpose of illustration and forms no part of the claimed design.

FIG.1

FIG. 2

FIG. 3

FIG. 4

FIG. 5
